UNITED STATES PATENT OFFICE.

LAROY VINCENT, OF CUYLER, NEW YORK.

DESIGN FOR A MEMBER OF STAPLE-EXTRACTING TOOLS.

SPECIFICATION forming part of Design No. 29,903, dated December 27, 1898.

Application filed November 30, 1898. Serial No. 697,915. Term of patent 7 years.

To all whom it may concern:

Be it known that I, LAROY VINCENT, a citizen of the United States, residing at Cuyler, in the county of Cortland and State of New York, have invented and produced a new and original Design for the Member of a Staple-Extracting Tool, of which the following is a specification.

My invention relates to a new and novel design for the member of a staple-extracting tool; and the leading feature thereof consists in the peculiar configuration given to the jaw thereof, whereby it may be readily distinguished from other tools for a similar purpose now in common use.

In the accompanying drawings, Figure 1 is a perspective view of the member of a staple-extracting tool constructed in accordance with my design. Fig. 2 is a detail front view of the jaw.

In the said drawings the numeral 1 designates the handle of the tool, and 2 the curved jaw, formed with an extension 3 at one side. At the front end of the jaw there is formed a side extension 4, which is integral with the extension 3. The said jaw is also formed with a slot 5 at the front end.

From the above it will be seen that my design presents distinguishing differences from others now in use and also presents a neat and attractive appearance.

Having thus described my invention, what I claim is—

The design for the member of a staple-extracting tool, substantially as herein shown and described.

In testimony whereof I have hereunto set my hand in presence of two subscribing witnesses.

LAROY VINCENT.
